UNITED STATES PATENT OFFICE.

GEORGE T. LADD, OF PITTSBURGH, PENNSYLVANIA.

BOILER.

1,326,203.

Specification of Letters Patent. Patented Dec. 30, 1919.

Application filed February 28, 1916. Serial No. 80,947.

To all whom it may concern:

Be it known that I, GEORGE T. LADD, residing at Pittsburgh, in the county of Allegheny and State of Pennsylvania, a citizen 5 of the United States, have invented or discovered certain new and useful Improvements in Boilers, of which improvements the following is a specification.

The fire box or combustion chambers of 10 single unit vertical water tube boilers are necessarily arranged at one side of the boiler and are substantially box shaped, having a top, a front and two side walls, the fourth side being open for the flow of the products 15 of combustion, the heating or boiler chamber. In such a construction there is a great loss of heat by radiation from said walls. In the multiple unit type of vertical water tube boilers, the fire box or combustion chamber is generally located between two adjacent units, which therefore form two sides of the fire or combustion chamber. But there is a great loss of heat by radiation from the end walls of the fire 25 or combustion chamber.

The invention described herein has for its object, the arrangement of a portion of the heating members in such a position in the combustion chamber as to utilize the 30 heat heretofore lost by radiation, in the generation of power. The invention is hereinafter more fully described and claimed.

In the accompanying drawings forming a part of this specification, Figure 1 is a 35 view partly in front elevation and partly in section of a vertical water tube boiler embodying my improvement; Fig. 2 is a sectional elevation, the plane of section being at right angles to the axes of the drums; Fig. 3 is a sectional plan view, the plane of 40 section being indicated by the line III—III Fig. 1; Fig. 4 is a sectional elevation of a multiple unit vertical water tube boiler embodying my improvement, the plane of section being indicated by the line IV—IV Fig. 5; Fig. 5 is a sectional elevation on a plane indicated by the line V—V Fig. 4; Fig. 6 is a sectional detail illustrating a 45 modification of my improvement, and Fig. 7 is a sectional plan view on a plane indicated by the line VII—VII Fig. 6.

While in the practice of my invention, it is preferred to employ the construction of boiler setting and combustion chamber described and shown in an application filed of even date herewith, it will be understood

that as regards its broader features my improvement can be embodied in other forms or constructions of boilers, and the broad terms of the claims are not limited to any specific construction of combustion chamber or fire box.

In the construction shown in Figs. 1, 2 and 3, the boiler proper consists of upper and lower drums 1 and 2, which are connected by three sets of tubes, 3, 4 and 5. This boiler is inclosed on the rear and two sides within suitable walls as is customary, and the front of the setting is constructed to provide a suitable fire box or combustion chamber. While not necessary to the successful employment of the invention described and claimed herein, it is preferred to make a high combustion chamber as shown in Figs. 1 and 2, and described and claimed in an application filed February 28, 1916, Serial No. 80948, Patent No. 1283814.

As shown, the combustion chamber is so constructed that the highest part of the arch 6, forming the top of the chamber is in or approximately in a level with the axis of the upper drum 1. It will be readily understood by those skilled in the art, that the front and side walls of a combustion chamber whether of the high or low arch type are very highly heated and consequently there will be a great loss of heat by radiation from said walls. In order to utilize in part at least, the heat now lost, provision is made for arranging a superheater in suitable relation to one or more of the walls dependent upon the size of the boiler and the relative capacities of the boiler and superheater.

A desirable construction of the wall of the fire box and arrangement of superheater consists in providing an open topped pocket 7 for the reception of the superheater 8, which may be of any desired construction. This pocket is formed by extending the side 100 walls so that the upper portion 9 of the front wall will extend beyond the lower portion 10 and building up on the latter, a screen wall 11, a suitable distance inside the portion 9 of the front wall. As shown 105 in Figs. 1 and 2, this screen wall does not extend to the top of the combustion chamber, so that there is an opening provided for the entrance of products of combustion into the top of the pocket. As the superheater 110 is substantially cooler than the products of combustion, the gases coming into contact

with the superheater will be reduced in temperature, thereby reducing the pressure in the pocket, so that the gases will flow into the upper end of the pocket down along the 5 superheater tubes and then back into the combustion chamber through openings 12 in the screen wall 11. As shown in Figs. 1, 2, 4 and 5, a plurality of openings of different heights may be formed through the 10 screen wall, or the gases may escape from the pockets through openings 12^a at the lower ends of the pockets. The superheater will be subjected to heat radiated from the outer wall of the furnace and from the 15 screen wall, and also by convection by the gases flowing through the pockets as described. In order to prevent excessive heating of the superheater, dampers 13 may be employed as shown in Figs. 6 and 7 for controlling the flow of gases through the 20 pockets.

In applying my improvement to multiple unit boilers, which have the combustion chamber arranged intermediate, the boiler 25 units as shown in Figs. 4 and 5, the pockets 7 for the superheater are arranged outside of one or both end walls of the combustion chamber, and an opening 14 is formed through the end wall for the passage of the 30 hot gases into the upper ends of the pockets, and said end walls which in this construction become the screen walls are provided with openings 12 or with dampered openings 12^a for the flow of gases from the 35 pockets back into the combustion chamber.

It is characteristic of my improvement that the wall or walls of the combustion chamber are protected by the superheater, and that the latter are to a large extent 40 heated by heat units heretofore lost. And

further the gases, which contact with the superheater are regenerated before reaching the tubes or other surfaces of the boiler.

I am aware that it is old to arrange super-heating coils in a pocket outside of the 45 wall of a combustion chamber for a boiler, said chamber narrowing progressively toward its upper end and having in its outer wall for the flowing of products of combustion into the super-heater, a pocket from 50 which the gases escape through an outlet traversed by the upper ends of the boiler tubes.

I claim herein as my invention:

1. In a boiler of the vertical water tube 55 type, the combination of a combustion chamber, one of the inclosing walls of said chamber being provided with a pocket provided with openings into the combustion chamber permitting of the flow of products of combustion from the combustion chamber down through the pocket and back into the combustion chamber, and a superheater arranged in said pocket.

2. In a boiler of the vertical water tube 65 type, the combination of a combustion chamber, one of the inclosing walls of the chamber being provided with an open-topped pocket, the top of said pocket being unobstructed and located a substantial distance 70 below the top of the combustion chamber, the inner wall of the pocket being provided with openings for the flow of gases into the combustion chamber; and a superheater arranged in said pocket.

In testimony whereof, I have hereunto set my hand.

GEORGE T. LADD.

Witness:
G. G. TRILL.
